INVENTOR
Henry H. Pals,
BY
Arthur M. Hood.
ATTORNEY

UNITED STATES PATENT OFFICE.

HENRY H. PALS, OF MESERVEY, IOWA.

STOCK DOOR.

Application filed September 18, 1922. Serial No. 588,982.

To all whom it may concern:

Be it known that I, HENRY H. PALS, a citizen of the United States, residing at Meservey, in the county of Cerro Gordo and State of Iowa, have invented a new and useful Stock Door, of which the following is a specification.

My invention relates to improvements in swinging doors and particularly to that type of swinging doors used in stock pens and the like, which are held normally yieldingly in a medial position and which are capable of swinging in either direction.

One of the objects of my invention is to provide a door of extremely cheap construction, which however, will be of such character that stock cannot be injured by projecting parts and which may be readily assembled and placed in position.

For the purpose of disclosing my invention I have illustrated one embodiment thereof in the accompanying drawings in which;

Fig. 1, is a side elevation of a door partially in section and embodying my invention;

Fig. 2, is a sectional view taken on the line 2—2 of Figure 1;

Fig. 3, is a plan view;

Fig. 4, is a partial end elevation partially in section and showing the door open;

Fig. 5, is a detail partly in section of the end shield, and

Fig. 6, is a detail section on the line 6—6 of Fig. 1.

As illustrated in the drawings the door frame 1 may be either an integral or structural part of a stall, fence, door, partition, or the like. The swinging door 2 is formed of a plurality of boards 3 held together by rods 4 which pass through the boards horizontally. The pivot edge of the door is preferably concaved as at 5 to form a seat for the pivot rod 6. This rod is tubular in form and extends from end to end of the door and at suitable intervals is provided at its outer surface with openings 7 to permit the insertion therethrough of the clamping rods 4. As shown in Figs. 1 and 2 these rods extend through the pivot rod having their heads 8 engaging the pivot rod

and at their opposite ends are provided with tap nuts 9 whereby by tightening the nuts 9 the boards 3 comprising the door are securely held together and the hollow pivot

rod 6 held in its seat on the edge of the door. At each end of the pivot rod 6 I provide pivot pins 10 which are preferably formed on plates 11 and project into the pivot rod. These plates are secured to the top and bottom portion of the frame and with the pivot pins 10 inserted in the rod at the top and bottom of the pivot rod as illustrated, provides spacers to slightly separate the top and bottom of the door from the frame and also wear plates for the pivot rod.

The free end of the door is provided with a shield 13 preferably formed of metal and being U-shaped in cross section so that a rounded edge 14 is provided. The two legs of the shield straddle the edge of the door and are secured to the door by bolts 15 passing through horizontal slots formed in the shield. The provision of the slots permits of a lateral adjustment of the shield so that same may be very nicely adjusted with respect to the side member of the frame. This shield forms a hollow edge member which accommodates the weight 16 secured to the end of a cable 17, the opposite end 18 of which is secured in the frame immediately above the shield. This weight and cable tend to hold the door in its medial position but at the same time permit the door to yield in either direction under pressure, bringing the door however, back to its closed position as soon as said pressure is removed.

For locking in closed position I provide a pin 19 which passes through the frame and into a socket in the door.

I claim as my invention:

1. A swinging door formed of a plurality of boards placed edge to edge, a hollow hinge rod extending along the rear edge of the door and clamping bolts extending laterally through said rod and the boards, for clamping the boards together and holding the hinge rod in position.

2. A door formed of a plurality of boards arranged edge to edge, the hinge edge of said door being concaved, a hollow hinge rod seating in said concave portion and a plurality of bolts extending through said boards and rod to clamp the boards together and secure the rod in position.

3. A swinging door formed of a plurality of boards placed edge to edge, a hollow hinge rod, bolts extending through said rod and door to clamp the boards together and

- secure the rod in position, and a **U** shaped sheet metal shield secured over the free edge of the door. 25
4. A door comprising a frame, a swinging door supported in said frame comprising a plurality of boards placed edge to edge, a hollow hinge rod arranged at one edge of the door, bolts passing through said rod and the door to clamp the boards 30
- 10 of the door together and hold the hinge rod in position, a hollow **U** shaped shield secured over the free edge of the door and having its front portion spaced apart from the front edge of the door to form a channel, and a cable having its upper end secured to the frame and its opposite end secured to a weight operating in said channel and arranged to yieldingly hold the door in a medial position. 35
- 15 5. A swinging wooden door, a tubular hinge rod extending along the side edge of the door, and clamping bolts extending trans- 40
- versely through said rod and door for securing said rod and door in fixed relation to each other. 45
6. A swinging door having its hinge edge concaved, a tubular hinge rod seating in said concavity, and clamping bolts extending transversely through said rod and door for securing said rod and door in fixed relation to each other. 50
7. A door structure comprising a frame, a pair of inwardly projecting stub shafts secured to said frame, a tubular rod journaled on said shafts, a wooden door, and clamping bolts extending transversely through said rod and door for securing said rod and door in fixed relation to each other. 55

In witness where, I, HENRY H. PALS, have hereunto set my hand at Sheffield, Iowa, this 12th day of September, A. D. one thousand nine hundred and twenty-two. 60

HENRY H. PALS.
